UNITED STATES PATENT OFFICE.

TOM J. JOHNS, OF CLEVELAND, OHIO, ASSIGNOR OF ONE-FOURTH TO CLEOTRA OSAKO, OF CASPER, WYOMING.

SPRING-CUSHIONED DRAWBAR AND DRAWHEAD FOR RAILWAY CARS.

Application filed August 12, 1924. Serial No. 731,612.

To all whom it may concern:

Be it known that I, Tom J. Johns, a citizen of the United States, residing at Cleveland, in the county of Cuyahoga and State 5 of Ohio, have invented certain new and useful Improvements in Spring-Cushioned Drawbars and Drawheads for Railway Cars, of which the following is a specification, reference being had to the accompanying 10 drawings.

This invention relates to railway trains, and particularly to the draw bars thereof.

The general object of the invention is to provide a structure which will minimize the 15 amount of jerks and jars which are transmitted to the railway cars through the couplings thereof.

A further object is to provide a construction of this character wherein these jerks 20 and jars are minimized by the use of springs yieldingly holding the draw bar in a normal position but yielding upon any forward jerk being transmitted to the draw bar or upon a rearward thrust being transmitted 25 to the draw bar.

A still further object is to provide a draw bar with a draw head which is capable of lateral movement to permit freedom of movement of the cars in turning curves.

Another object is to provide a draw head 30 which is readily detachable from the draw bar in case of breakage.

Still another object is to provide a draw bar and draw head so constructed that the 35 strain will be applied through the car over a relatively large area, thus reducing strain on any particular part of the car and minimizing the chance of the draw bar breaking.

Other objects will appear in the course of 40 the following description.

My invention is illustrated in the accompanying drawings, wherein:

Figure 1 is a top plan view partly broken 45 away of my improved draw bar assembly;

Figure 2 is a plan view of a coupler and draw bar with the top plate removed;

Figure 3 is an enlarged fragmentary top 50 plan view of a portion of the car frame, my draw bars applied thereto;

Figure 4 is a longitudinal section on the line 4-4 of Figure 3;

Figure 5 is a section on the line 5-5 of Figure 3;

Referring to these drawings, 10 designates

parallel car sills which are connected at opposite ends to the transversely extending brace bars 11 which are bolted to the end of the car frame or engaged therewith in any suitable manner. Each of the sills 10 60 is formed with a longitudinally extending opening 12 having inwardly extending shoulders 13 disposed at the middle of this opening.

Extending transversely across the car are 65 the two parallel cross heads 14, each cross head being connected to a draw bar 15, which in turn is connected to a draw head 16 whose details will be later described. Each draw bar passes through a slot 17 70 formed in the brace 11, this slot being sufficiently wide as to permit lateral play of the draw bar and head. Each draw bar may also be supported in a guide 18 mounted between the sills 10, this guide being sufficiently large to permit of play. Each cross head 14 is free to reciprocate between the medially disposed shoulder 13 and the end wall of the opening 12, but each draw bar is restrained from reciprocation by means 75 of springs 19 and 20. Rods 21 pass entirely through the space 12 from one end wall of this space to the other, and each cross bar 14 is formed with a plurality of openings 80 23 through which these rods pass. The springs 19 are disposed around the rods 21 and between the cross heads 14, while the springs 20 are disposed around the rods 21 but between each cross head and the adjacent end wall of the opening 12. These springs 90 20 are compression springs. Preferably there are six of these springs 19 engaged with the two cross heads 14 and there are six of the springs 20 engaged with each cross head.

It will thus be seen that when a cross 95 head is thrust toward the center of the car that it compresses the springs 19 and when it is pulled toward the end of the car it will compress the springs 20. In addition to the springs 19 and 20, each cross head 100 is provided with the longitudinally extending rod 24 which passes through openings 25 in each cross head, the extremities of the rod being mounted upon brackets 26. Disposed between each of these brackets 26 105 and the adjacent cross head and surrounding the rod 24 are the coiled springs 27 so that these springs also assist in resisting movement of the cross heads 14 and thus yieldingly resisting movement of the draw 110

bars 15. Each draw bar 15 is longitudinally recessed at its outer end, as at 28, the side walls of the recess being transversely apertured, as at 29.

5 Coacting with each draw bar is the draw head 30 carrying a coupling member 31. This draw head extends into the draw bar longitudinally along the opening 28. The opening 28 is enlarged adjacent its rear end 10 and the draw bar is formed with laterally projecting portions 32 which engage in this enlarged part of the opening 28 and specifically between the shoulders 33 and 34 which are formed upon the lateral walls of the 15 opening 28. A shoulder 35 extends inward medially from the rear wall of the opening 28 and the draw head is formed with a medially disposed portion 36 adapted to abut against this shoulder 35 when the draw head 20 is forced rearward. Chains 37 are attached to the draw head at one end by means of hooks 38 from which the chains may be readily released and at their other ends are attached to the rear wall of the opening 28. 25 The draw head 30 is formed with a transversely extending slot 39, and passing through this slot and through the side walls of the opening 28 is a bolt 40, this slot being large enough to permit the movement of the 30 draw head. Any ordinary coupling 31 may be used. The chains 37 permit the movement of the draw head forward and rearward or laterally. This lateral movement of the draw head is also permitted by the 35 relatively wide slot 39 through which the bolt 40 passes, and this permits the cars to readily swing around curves. In case the lip of the draw head should break, the draw head can be taken out from the car in ten 40 minutes by just unhooking the chains 37 and pulling out the pin 40, but there is very little likelihood of the lip on the draw head breaking in view of the fact that the draw bar is yieldingly cushioned upon any sudden 45 forward thrust or rearward thrust.

It will be seen that this construction will tend to prevent the quite common occurrence of draw bars pulling out and also prevent the jars, shocks and jolts which are given to a train both by the jarring of the cars against each other and by the jars and shocks given to it when the engine suddenly starts ahead or brakes are suddenly applied, or when the cars are coupled. It will further be seen that the strains on the car and draw bars and draw heads are distributed so that very little strain comes on one part of the car, thus conserving the life of the cars.

50 60 I claim:

1. In a railway car, longitudinally extending sills, each sill having a longitudinally extending opening therein defined by upper and lower longitudinally extending members

having inwardly and downwardly projecting shoulders, these shoulders constituting bumpers, draw bars extending inward from opposite ends of the car and each draw bar having a cross head extending transversely of the car and into the openings in the sills 70 and between said longitudinally extending members and being guided thereby, the extremities of each cross head operating between a bumper and the adjacent end walls of the sill openings, springs disposed between the ends of each cross head and the adjacent end wall of the sill, and springs disposed between both cross heads, said springs acting to yieldingly resist movement of the cross heads in either direction. 80

2. In a railway car, longitudinally extending sills, each having a longitudinally extending opening at its middle, each opening communicating with the space between the sills, longitudinally extending draw bars disposed between the sills and each extending to one end of the car and having a coupling at its outer end, the inner end of each draw bar being provided with a transversely extending cross head extending into the opening in the sills, the openings in the sills having medially disposed bumpers, rods attached to the end walls of said sill openings and extending longitudinally, the cross heads being formed with passages through 95 which said rods pass, and coiled springs surrounding said rods on opposite sides of the cross head and resisting longitudinal movement of the draw bars and cross heads. 90

3. In a railway car, longitudinally extending sills, each having a longitudinally extending opening at its middle, each opening communicating with the space between the sills, longitudinally extending draw bars disposed between the sills and each extending to one end of the car and having a coupling at its outer end, the inner end of each draw bar being provided with a transversely extending cross head extending into the opening in the sills, the openings in the sills 100 having medially disposed bumpers, rods attached to the end walls of said sill openings and extending longitudinally, the cross heads being formed with passages through which said rods pass, coiled springs surrounding 110 said rods on opposite sides of the cross heads and resisting longitudinal movement of the draw bars and cross heads, brackets attached to the inner faces of the sills, rods attached to the ends of said brackets and extending through apertures in the cross heads, and springs coiled around said rods and bearing against the cross heads and against said brackets and resisting movement of the cross heads toward the ends of the car. 115

In testimony whereof I hereunto affix my signature.

TOM J. JOHNS.
